UNITED STATES PATENT OFFICE.

WILLIAM W. MILLER, OF SHILLINGTON, PENNSYLVANIA.

STOP-COCK.

No. 885,775.

Specification of Letters Patent. Patented April 28, 1908.

Application filed April 4, 1907. Serial No. 366,300.

To all whom it may concern:

Be it known that I, WILLIAM W. MILLER, a citizen of the United States, and a resident of Shillington, in the county of Berks and 5 State of Pennsylvania, have invented certain new and useful Improvements in Stop-Cocks, of which the following is a specification.

My invention relates to cocks or valves in which a turning plug is employed having a 10 limited rotary movement in the casing limited by a lateral projection provided upon the plug to contact with a stop or offset upon the rim of the casing.

My object is to simplify and improve the 15 plug construction, and my invention consists in providing the plug with a separately formed sheet metal handle having an integral wing portion adapted to form such lateral projection upon the plug when applied to the 20 latter, as fully described in connection with the accompanying drawing and specifically pointed out in the claims.

Figure 1 is a side elevation of a cock embodying my invention. Fig. 2 is a separate 25 view of my improved separately formed handle for the turning plug; and Fig. 3 is a separate view of the slotted plug.

C represents any ordinary cock or valve 30 casing having a plug opening intersecting the passage-way a therethrough, and P represents an ordinary turning plug with lateral 35 opening b adapted to register with said passage-way a or to close the same as desired. A portion of the rim c of the casing, as shown, 40 is cut down to form offsets d, as usual, for limiting the rotation of the plug; and a separately formed sheet metal handle H is secured to the protruding head or handle end e of the plug, which general construction is well known.

My improvement consists in so forming 45 the sheet metal handle H and applying it to the plug, as to thereby provide the latter with the lateral projection whereby, in co- operation with the offsets d, its rotation is limited as desired; the object being to avoid

the necessity of forming such projection by additional operations as heretofore, and at the same time secure a more permanent and satisfactory stop device. To this end I form 50 the handle H with a depending wing portion f, formed integral therewith as indicated by punching the same from sheet metal without involving any additional operation whatever; and I so form the slot g in the plug 55 head e that when the handle H is properly seated therein, said wing f will project laterally from the inserted plug below the top of the casing rim; the slot g being cut obliquely, as shown, so as to firmly support 60 said depending wing portion of the handle when the latter is riveted or otherwise secured to the plug. By thus forming the lateral plug projection as an integral part of the sheet metal handle, not only is a considerable 65 economy and great simplicity of construction attained, but greater rigidity and longer wear are secured, with flatwise contact of the handle projection against the rim offsets d.

What I claim is:—

1. A turning-plug for stop cocks having a sheet metal handle rigidly secured to the protruding head thereof and formed with a wing portion projecting laterally from the body of the plug to serve as a stop to rotary motion 75 thereof in the casing.

2. The combination with a stop cock casing having an offset rim, of a turning plug having a protruding head provided with a handle-slot extending into the tapered body 80 of the plug, and a sheet metal handle rigidly secured in said slot and formed with a wing portion projecting laterally from the body of the plug to serve as a stop against said rim offset, substantially as set forth. 85

In testimony whereof, I affix my signature, in the presence of two witnesses.

WILLIAM W. MILLER.
